UNITED STATES PATENT OFFICE.

JUAN ANTONIO OTERO, OF LA PLATA, ARGENTINA, ASSIGNOR TO GENARO WILLIAM COOKE, OF LA PLATA, ARGENTINA.

ELECTRIC INTERRUPTER.

Original application filed December 26, 1917, Serial No. 208,877. Divided and this application filed March 7, 1922. Serial No. 541,802.

To all whom it may concern:

Be it known that I, JUAN ANTONIO OTERO, citizen of the Argentine Republic, and resident of La Plata, Argentina, have invented certain new and useful Improvements in an Electric Interrupter, of which the following is a specification.

This invention relates to an interrupter which is described in the specification filed 10 under date of December 26th 1917 under Number 208,877, being a divisional application thereunder.

To facilitate the explanation of the invention, a sample apparatus embodying it is 15 illustrated in the accompanying drawing, in which:

Fig. 1 is a view of the interrupter;

Fig. 2 is a detail in enlarged scale of a 20 part of the interrupter, showing in dotted lines the different positions of some of the parts.

In the drawings, like parts are indicated by similar characters in all the figures.

The apparatus embodying the interrupter 25 consists of four principal parts: the interrupter proper, the transformer, the condenser and a resistance, the construction being as follows:

Interrupter.

The interrupter (Fig. 1) is formed by a core A, of small soft iron wires, with a total diameter of 17 millimeters by nine centimeters in length. On this core there 35 is wound a coil P of covered copper wire having a diameter of approximately $\frac{2}{10}$ to $\frac{3}{10}$ of a millimeter.

In front of the said core A and held by a steel spring D, is located an armature piece 40 E of soft iron, in such a way that it may be attracted by the energizing of the core A.

In the central part of this armature piece E and opposite to the core A, a cylindrical contact A' of German silver or nickel having 45 a diameter of from 5 to 6 millimeters, is either screwed or riveted.

In front of this contact piece A' there is a similar contact A'' of the same metal and similar diameter, attached to a brass adjusting screw F which in its turn is held by a standard G, also of brass.

At the end opposite to the contact the said screw has a fibre or ebonite disk H by means of which it may be turned without

danger of the current passing to the hand of 55 the operator.

Between the contacts A' and A'' there is placed a disk X of nickel or German silver, having an inclination of forty-five degrees with relation to the axis of said screw F, 60 said disk X being held by a small steel or brass spring 1 adapted to be placed either on the top or bottom side.

Said disk X is given the following movements when the interrupter is operated: first, 65 a forward movement; second, a movement in the direction of its plane; and third, a rocking movement; all of these movements serving to change constantly the points of contact through which the current passes. 70 Furthermore, by this device the two points of contact are formed at different levels or planes.

As best shown in Fig. 2, the nickel cylinders A' and A'' are not in the same plane, 75 A'' being slightly higher than A', so that the points of contact with the inclined disk X (also nickel) are made at a different level. The current, in passing through the interrupter, is attracted by the energizing of the 80 core A and the iron piece E, thus changing the position of the inclined disk X and producing two spark breaks or interruptions, one at the lower port of the cylinder or contact A' and upper face of disk X, and the 85 other at the upper part of the cylinder A'' and lower face of disk X. At the same time these two points of contact constantly change position on account of the movement imparted to the disk X, as indicated by the 90 dotted lines in Fig. 2.

The principal feature of the interrupter of my invention lies in the fact that the contacts A' and A'' are not on the same level as in the usual types, this difference of level 95 having been found indispensable for the highest efficiency. This feature together with the resiliently suspended disk between the two contacts constitute a complete novelty over all known forms of interrupter and 100 produce the technical effects described hereinbefore.

It has been found in practice that this arrangement of devices gives a very high efficiency and regularity in the production of 105 high frequency currents, and this interrupter with the inclined disk X as above described is fundamental in this apparatus

since with it there may be obtained with the greatest regularity a current of very high frequency.

The diameter of the wire in the coil carried by the core A, as also the size of the latter, may be varied according to the size and capacity of the apparatus to be constructed.

Having thus described my invention, what I claim and desire to protect by Letters

19 Patent of the United States of America, is:

In an interrupter for electrical circuits, the combination of an electro-magnet, a vibrating armature attracted by said electro-magnet, said armature being provided, on 15 the side opposite from the one facing the

magnet, with a projecting contact piece, a stationary contact facing the said contact piece of said vibrating armature at a different level therefrom, and means to complete the contract between said vibrating armature and said fixed contact, said means consisting of a metal disk resiliently suspended in an inclined position between said armature and said fixed contact. 20

Signed at Buenos Aires, Argentine Republic this 30th day of May A. D., 1921. 25

JUAN ANTONIO OTERO.
